WALTER C. LINDEMANN AND GUSTAV C. LORENZ, OF MILWAUKEE, WISCONSIN, ASSIGNEES TO A. J. LINDEMANN & HOVERSON COMPANY, OF MILWAUKEE, WISCONSIN, A CORPORATION OF WISCONSIN

WICK BURNER

Application filed June 1, 1931. Serial No. 541,348.

The improvements relate to burners in which liquid hydrocarbon fuel is used and is vaporized and burned at the top of a capillary wick, and more particularly to means for holding the wick device in proper position between the wick tubes and permitting it to be inserted and removed therefrom, to maintain its position and to work therein without difficulty, and also for protecting it against the danger of combustion below its top and from the clogging and other undesirable effects of falling carbon or other foreign matter to which it and the fuel in the lower part of the tubes may be exposed.

Heretofore it has been the practice to some extend to have the outer wick tube terminate a considerable distance below the top of the inner wick tube, and to provide the outer wick tube with a removable head extending up to the top of the outer wick tube, so that this head can be removed to give access to the wick, when it is necessary to remove and replace it. This head is sometimes provided with an inwardly extending portion and a collar depending therefrom and extending downwardly alongside the wick to space the wick from the outer wall of the head and secure it in position. Such heads, however, sometimes give rise to undesirable results, since they are required to be very accurately made and fitted, and very carefully positioned, and unless so made and positioned will cause bad combustion liberating smoke and gases to contaminate the atmosphere and foul cooking utensils, and may even permit the highly inflammable vapor generated at the top of the wick to gravitate down between the tubes and set up dangerous combustion there.

The primary objects of the present improvements are to provide a wick spacing and holding device between the wick and the outer tube of simple and easily manipulated form and efficient and dependable character, which will permit the outer wick tube to extend substantially to the top of the inner wick tube, will seal off the space between the outer tube and the wick and provide an accurate and stable base for the combustion tubes usually employed in connection there-

with, for cooking and other purposes to produce a blue flame.

Other usefulness and advantages will be understood by those familiar with the manufacture and use of burners of this character.

The improvements are illustrated in the accompanying drawing, in which—

Figure 1 is a side view, partly in perspective, showing the tops of wick and wick tubes, with the wick holding device in position, embodying the improvements, the upper part of the outer tube being broken away to expose the wick holder and spacer, which is shown in vertical section;

Figure 2 is a view similar to Fig. 1 of the said wick holder and spacer removed from the tubes;

Figure 3 is a half side elevation and half vertical section of the parts shown in Fig. 1, with the combustion tubes and their outer shield mounted thereon, the latter being broken off just above their bottoms.

The inner wick tube 1 has an inwardly projecting annular flange 2 at its top supporting a cross member 3, which may be employed as a guide for an ordinary combustion chamber raising and lowering device, and has an upstanding annular rim 4 formed by folding over the upper edge of the tube. The flange 2 is the usual support for the bottom edge of the inner combustion tube 5 and the rim 4 the means for holding it in position thereon. The collar of the outer wick tube 6 is provided with a similar flange 7 having a like rim 8 formed in the same manner as the rim 4, for supporting the outer combustion tube 9. The combustion tubes 5 and 9 may be secured together in the usual manner, and surrounded by a wind shield 10, preferably secured to the combustion chamber by the same means. The parts so far described are all of usual and ordinary form, and have been well known and extensively used for many years.

The flange 7 of the outer wick tube 6 is not formed on that tube, but is formed on the top of a collar which has its lower portion provided with curved grooves 12 adapted to engage short beads 13 on the inner side of the wick tube 6, the grooves 12 having open

portions 12', which receive the beads 13 when the collar is pressed down inside the tube, and horizontal portions 12'', which hold them in the upper ends of said grooves after the collar has been rotated clockwise to bring the parts to this position, so that accidental rotation and a resulting relative movement of the parts will be prevented. In this position, the flange 7 is in close contact with the upper edge of the tube 6, and its peripheral bead 7' is in overlapping relation to said edge, whereby a seal between these parts is provided. It is not necessary, however, that the beads 13 shall be lodged in the horizontal ends 12'' when the collar is "home" and the flange 7 in contact with the upper edge of the tube 6, as the friction between the beads and the grooves will be sufficient to hold them at any point in the groove. The groove, however, should be of sufficient length to take care of slight variations in the location of the beads and grooves and in the length of the outer tube, so that rotation of the collar will always bring the flange 7 down until it presses against the upper edge of the tube, and, with the assistance of the peripheral bead 7', makes a good closure.

The collar has an inwardly and upwardly extending portion 14 and a vertical portion 15, so that it extends inwardly from the inner surface of the outer wick tube and then upwardly to form a space between it and the inner wick tube for the wick 16, the wick thus being held in position and permitted to move up and down between annular guides of limited depth on one side, so that it is rather closely confined, near its upper edge, without much friction. The space, however, is wide enough to permit the perforated wick liner 17 to be moved up therethrough to the top of the wick tube by the wick raising and lowering device 18.

The wick, its perforated metal sheath 17 and the wick raising and lowering device 18 are of usual form, and therefore require no further description.

It will be seen from the foregoing that the cutting off of the outer wick tube and the provision of a cap extending above the same, or any other extension of the outer tube are avoided by the present construction, and that the upper edge of the collar carrying the seat for the outer combustion cylinder is firmly and securely positioned on the top of the outer tube, and a seal formed between the flange 7 and the upper edge of said outer tube. The bead 7' not only assists in forming this seal and in securing the proper relative positions of the parts, but provides a slightly extending annulus which may be grasped by the fingers of the user for the purpose of rotating the collar and removing and replacing it. This bead may be milled or otherwise provided with an outer edge which will give a good purchase

for the fingers. It will also be seen that the space between the wick and the outer wick tube at the top is sealed off from the space between the wick tubes and that the joint between the collar and the wick tube is spaced away from the oil saturated wick and extends an appreciable distance vertically, so that oil from the wick cannot creep up through this joint, and reach the outer combustion cylinder or the outside of the outer wick tube. The fact that the base flange 7 rests squarely on the top of the outer wick tube, and is in effect integral therewith, ensures a firm and accurately positioned base for the combustion chamber on the outside, and avoids any undesirable results due to the expansion or contraction of the metal or slight inaccuracies which may occur in the manufacture of the parts, which is not the case where a head or other extension of the outer wick tube is used and is mounted on the wick tube by means of a connection having a limited area located at a point distant from the point at which the combustion tube is supported.

The desirability of insulating the wick tube from the combustion in the combustion chamber, and the heat of the combustion chamber cylinders and their seats communicated to them from the combustion chamber, has been appreciated for many years, and various devices have been used to effect this purpose. It is believed, however, that the present improvements have advantages over all others in this respect; and if desired, the portion of the wick tube at 19, opposite the vertical portion 15 of the collar, may be provided with perforations to permit the circulation of air through the chamber 20 between these parts for the cooling of the parts.

The perforations 21 in the outer fold of the outside combustion tube holding rim 8 may be employed, whether or not the top of the wick tube is perforated, to provide an outlet of air from the chamber 20, and support combustion at the bottom edge of the outer combustion tube 9. These perforations should be of about the same calibre as those of the combustion cylinders—which follow the well known formula for blue flame combustion—and not more numerous, so that a very limited supply of air is given thereby, and at the same time an upward movement imparted to the air in the chamber 20 to ventilate it and promote cooling. By this provision also a small volume of air may be permitted to enter the chamber through the joints, and any slight amount of oil creeping up through the lower joint will be taken care of by evaporation and venting.

What we claim is:

1. The combination with outer and inner concentric wick tubes having a space therebetween for a wick and a combustion cham-

ber mounted thereon, of a collar supported below the top of and inside the outer wick tube having a portion extending inwardly to contact with a wick and upwardly to the 5 top of said outer tube and a portion extending outwardly therefrom.

2. The combination with outer and inner concentric wick tubes having a space there-between for a wick and a combustion chamber mounted thereon, of a collar supported below the top of and inside the outer wick tube having a portion extending inwardly and upwardly to the top of said outer tube and a portion supported thereby extending 10 outwardly therefrom and over the upper edge of the said outer tube.

3. The combination with outer and inner concentric wick tubes having a space there-between for a wick and a combustion chamber mounted thereon, of a collar supported below the top of and inside the outer wick tube having a portion extending inwardly and upwardly to the top of said outer tube and a portion extending outwardly therefrom 15 and over the upper edge of the said outer tube, said last named portion having an edge portion supported thereby projecting beyond 20 said wick tube and below its upper edge.

4. The combination with outer and inner concentric wick tubes having a space there-between for a wick and a combustion chamber mounted thereon, of a collar supported below the top of and inside the outer wick tube having a portion extending inwardly and upwardly to the top of said outer tube and a portion extending outwardly therefrom and over the upper edge of the said outer tube and means for securing the said collar in position and maintaining said last 25 named portion pressing against the upper edge of said outer wick tube.

5. The combination with outer and inner concentric wick tubes having their upper edges substantially in the same plane and 30 having a space therebetween for a wick and a combustion chamber mounted thereon, of a collar supported below the top of and inside the outer wick tube having a portion extending inwardly and upwardly to the top of said outer tube and a portion extending outwardly therefrom.

6. A burner comprising spaced concentric outer and inner wick tubes providing a space between them for a wick and having their 35 upper edges substantially in plane, of a collar secured and supported inside the outer wick tube extending to the top thereof and having at its top a seat for a combustion cylinder closing the space between it and the outer wick tube.

7. The combination with outer and inner concentric wick tubes having a space there-between for a wick and a combustion chamber mounted and supported thereon, of a collar supported below the top of and inside

the outer wick tube having a portion extending inwardly and upwardly to the top of said outer tube and a portion extending outwardly therefrom there being a space between the inwardly extended portion of the 70 collar and the upper portion of the outer tube, the lower portion of the collar being in contact with the inner surface of the outer wick tube, whereby an air chamber closed at top, bottom and inner side is provided 75 beneath the combustion chamber.

8. The combination with outer and inner concentric wick tubes having a space there-between for a wick and a combustion chamber mounted and supported thereon, of a collar supported below the top of and inside the outer wick tube having a portion extending inwardly and upwardly to the top of said outer tube and a portion extending outwardly therefrom there being a space between the 80 inwardly extended portion of the collar and the upper portion of the outer tube, the lower portion of the collar being in contact with the inner surface of the outer wick tube throughout its circumference and an extended vertical area, whereby an air chamber closed at top, bottom and inner side is provided 85 beneath the combustion chamber.

9. The combination with outer and inner concentric wick tubes having a space there-between for a wick and a combustion chamber mounted and supported thereon, of a collar supported below the top of and inside the outer wick tube having a portion extending inwardly and upwardly to the top of said 90 outer tube and a portion extending outwardly therefrom, an upstanding flange formed in the collar at the junction therewith of the outwardly extending portion to position the lower edge of a combustion chamber outer cylinder on said outwardly extending portion, said flange having two spaced upright walls and the outer wall being provided with perforations.

10. The combination with outer and inner concentric wick tubes having a space there-between for a wick and a combustion chamber mounted and supported thereon, of a collar supported below the top of and inside the outer wick tube having a portion extending inwardly and upwardly to the top of said outer tube and a portion extending outwardly therefrom, an upstanding flange formed in the collar at the junction therewith of the outwardly extending portion to position the lower edge of a combustion chamber outer cylinder on said outwardly extending portion, said flange having two spaced upright walls and the outer wall being provided with 100 perforations, and there being a space between 105 the inwardly and upwardly extending portion of the collar and the said outer wick tube 110 with which said perforations communicate.

11. The combination with outer and inner concentric wick tubes having a space there- 115 120 125 130

between for a wick and a combustion chamber mounted thereon, of a collar having a substantial portion mounted below the top of and inside the outer wick tube, means for supporting said collar positioned substantially below the top of the outer wick tube, said collar having a portion extending inwardly and upwardly to the top of said outer tube and a portion extending outwardly therefrom.

12. The combination with outer and inner concentric wick tubes having a space therebetween for a wick and a combustion chamber mounted thereon, of a collar, a substantial portion of said collar mounted below the top of and inside the outer wick tube,

said portion extending inwardly and upwardly to the top of said outer tube, a portion extending outwardly therefrom, an upstanding flange formed in the collar at the junction therewith of the outwardly extending portion to position the lower edge of a combustion chamber outer cylinder on said last named portion, said flange having two spaced upright walls and the outer wall being provided with perforations, means for supporting said collar positioned substantially below the top of and on the inside of the outer wick tube.
